Geo. Kimmel. ATTORNEY.

UNITED STATES PATENT OFFICE.

WILLIAM S. HUMBLE, OF RIVERSIDE, CALIFORNIA.

SURGICAL INSTRUMENT.

Application filed January 20, 1927. Serial No. 162,376.

The invention relates to a surgical instrument, and more especially to the class of antrum openers and cleaners.

The primary object of the invention is the provision of an instrument of this character, wherein the tool such as a drill is supported and removably mounted in a holder or adaptor, so that the instrument can be fed through the nostrils of a patient to operate upon the infected antrum for cutting away diseased bone or other hard substances and thereafter the tool or drill removed, so that the antrum can be conveniently and easily cleaned.

Another object of the invention is the provision of an instrument of this character, wherein the adaptor or holder for the tool, such as a drill, is of novel form, whereby the tool or drill can be brought into proper position for operation upon the infected antrum of a patient, without liability of injury to the nostrils of such patient, when in the act of inserting the instrument or its removal therefrom and after operation upon the bone or other hard substances in the region of the antrum, the latter can be readily and conveniently cleaned by washing out such parts.

A further object of the invention is the provision of an instrument of this character, wherein a drain can be attached or the instrument when inserted in the nostril of a patient can be held in proper position for operation upon the patient, the instrument being of novel form to eliminate the possibility of the insertion thereof too far or in any manner injuring the tissues of the nostrils.

A still further object of the invention is the provision of an instrument of this character, which is extremely simple in construction, thoroughly reliable and efficient in its purpose, strong, durable, and inexpensive to manufacture.

With these and other objects in view, the invention consists in the features of construction, combination and arrangement of parts, as will be hereinafter more fully described in detail, illustrated in the accompanying drawing, showing the preferred embodiment of the invention, and pointed out in the claims hereunto appended.

In the accompanying drawing:—

Figure 1 is a side elevation of the instrument constructed in accordance with the invention. 55

Figure 2 is a fragmentary vertical longitudinal sectional view through the instrument.

Figure 3 is a sectional view on the line 3—3 of Figure 1 looking in the direction of 60 the arrow.

Similar reference characters indicate corresponding parts throughout the several views in the drawing.

Referring to the drawing in detail the 65 instrument comprises a curved tube 5, which is of the required length and size in cross section, preferably made from metal, although the same may be made from any other suitable material having a rounded or 70 beveled end 6, while the opposite end of said tube 5 emerges into an enlarged barrel 7, preferably straight and of the required length having formed therewith a shank 8 carrying a handle 9, the latter being made 75 detachably fast to the shank in any suitable manner. This handle 9 by reason of the form of the shank 8 is disposed at an angle 80 to the barrel 7 of the instrument and said handle is of the required length and external 85 configuration to meet the fancy of the user of the instrument.

Removably fitted in the tube and barrel 5 and 7 is a drill comprising a tip 10 which is projected through the free end of the tube 85 5 and this tip 10 is connected with a flexible stem 11 which is co-extensive with the length of the tube 5 and is adapted to conform to the conformation thereof, the stem 11 being joined with an axle 12 which fits within the 90 barrel 7, the said axle 12 being formed with a reduced shank 13 for detachable engagement in a socket or chuck 14 carried on the outer end of a flexible driving shaft 15 of any approved type. This driving shaft 15 95 is operated from any suitable source of power.

The drill including the tip 10, stem 11, and axle 12 is slidably held within the tube 5 and barrel 7 of the instrument and can be 100 readily removed therefrom, whereby said drill can be extracted after use.

The barrel 7 has formed thereon a cross head 16 having eye terminals 17 and said head 16 is formed with the barrel at an intermediate point thereof and constitutes a stop 105

2
to limit the insertion of the tube 5 within the nostrils of a patient and in addition will permit the attachment of a receptacle thereto in any suitable manner so that when the drill 5 has been removed from the tube 5 and its barrel 7 the instrument will serve as a drain and also as a nozzle for washing out the infected part. The instrument is used primarily for opening antrums and also for 10 washing out the infected antrum either before or after the drilling operation.

When the instrument is to be used as a nozzle for washing out infected parts, the drill is removed from the instrument and attached to the barrel 7 is a rubber tube (not shown) so that water or other liquid can be introduced through the barrel 7 and tube 5 and discharged from the end 6 of the latter directly onto the infected parts.

20 In the operation of the instrument the tube 5 is first inserted into the nostril of the patient and is held in proper position for operation on the antrum by means of the handle 9. Thereafter the drill is inserted 25 through the barrel 7 into the tube 5 so that the drill tip 10 will be disposed beyond the end 6 of the tube 5, whereupon the shank 13 is engaged in the chuck 14 on the flexible power shaft 15 and motion from the latter is 30 transmitted to the tip 10 which will cut through bone or other hard substances for the opening of the antrum. When this operation has been completed the drill is removed from the tube 5 and its barrel 7 so that the 35 part operated upon can be drained. Should it be desired to wash out the infected part a rubber tube is attached to the barrel 7 and water or other liquid can be introduced through said barrel 7 and tube 5 for discharge from the latter onto the infected part, the handle 9, being detached at this time. In this manner a sterile water or antiseptic 40 solution can be forced through the instrument into the antrum to wash it so as to wash the antrum in an easy and almost pain- 45 less manner.

If found desirable after the insertion of the tube 5 in the nostril of the patient a band or strap can be attached to the cross head 16 such band to encircle the head so as to retain the instrument in position without requiring the operator to hold such instrument by the handle 9 thereof until the period of drilling operation.

From the foregoing it is thought that the 55 construction and manner of use of the instrument will be clearly understood and therefore a more extended explanation has been omitted.

What is claimed is:

1. In an antrum drill and cleaner, a curved tube having an enlarged barrel at one end and opened at its opposite end, a handle connected with said barrel, and a drilling element removably insertable through the barrel and into the tube to have its drilling tip exposed through the open end of said tube.

2. In an antrum drill and cleaner, a curved tube having an enlarged barrel at one end 70 and opened at its opposite end, a handle connected with said barrel, a drilling element removably insertable through the barrel and into the tube to have its drilling tip exposed through the open end of said tube and a cross 75 head on the barrel intermediate the ends thereof and having eye terminals.

3. In an antrum drill and cleaner, a curved tube having an enlarged barrel at one end and opened at its opposite end, a handle connected with said barrel, a drilling element removably insertable through the barrel and into the tube to have its drilling tip exposed through the open end of said tube and a cross head on the barrel intermediate the 80 ends thereof and having eye terminals, the handle being disposed angularly with respect to the axis of the barrel.

In testimony whereof, I affix my signature hereto.

WILLIAM S. HUMBLE.
